UNITED STATES PATENT OFFICE

ELIE W. LABOMBARDE, OF NASHUA, NEW HAMPSHIRE

PAPER BOX

Application filed October 1, 1929. Serial No. 396,492.

This invention relates to paper receptacles and has particular reference to paper boxes of the set up type and having closable top or cover members.

5 The object of my present invention is to provide strong and durable set up boxes having integral cover members provided with side walls and which may be opened and closed a great many times without liability of 10 spilling the contents or mutilating the members which serve to provide continuity of the side walls of the top and bottom members of the boxes.

With the above stated object in view, the 15 invention consists in the boxes substantially as hereinafter described and claimed.

Of the accompanying drawings:

Figure 1 is a perspective view of one of the boxes in open condition.

20 Figure 2 represents a section on line 2—2 of Figure 1.

The above-mentioned views are sufficient to illustrate the present invention, in view of the fact that the said present invention is an 25 improvement on that illustrated and described in Letters Patent No. 1,021,874 issued to me April 2, 1912, to which reference may be had for some of the details of structure. For convenience of comparison, most of the 30 reference characters employed herein are the same as in said patent.

The chief differences between the present structure and that of the patent referred to are that the present box is of the permanently 35 set up type and all of the side walls are of double thickness, while the box of the patent is of the type that is collapsible to flat folded condition and has side walls of but single thickness.

40 Although boxes having double-thick side walls are well known, there is a special co-operation in my improved box, between the double-thick side walls and the members which serve as continuing or connecting side 45 walls between the double-thick walls of the bottom and top members, as will be explained hereinafter.

Referring to the accompanying drawings, the bottom of the box is illustrated at 20, to 50 which the top section 21 is connected by the

section 22. Integral with the section 20 are the two permanently upright side walls comprising outer sections 23 and inner sections 23' folded over inside and glued, thereby providing substantially stiff wall members. 55 The top or cover section 21 similarly has double-thick and glued side walls comprising outer sections 24 and in-folded and glued sections 24'. Preferably the end walls 14 and 15 are also of double thickness, the side walls 60 being notched as at 16.

Integral with and connecting the outer side wall sections 23, 24, are intermediate side wall sections of the box material creased on converging diagonal lines 25, 26, and slotted as at 27 to form triangular tongue flaps 28. These intermediate and connecting side wall sections just described are creased and slotted substantially the same as the similarly lettered parts of the box illustrated in the patent 70 referred to; and when the box is alternately opened and closed, the said creased and slotted side wall connections alternately straighten out and collapse or overfold as in said patent. In said patent however, the side walls of the 75 bottom and top members of the box were of single thickness, and necessarily so to enable the box to be collapsed to flat condition. Being of single thickness, and also creased to enable them to be folded to flat condition, they were insufficiently stiff to provide a box 80 for practical and repeated use. Frequently, and especially after a few openings and closings due to occasional dispensing of portions of the contents, the creases 25, 26, failed to function properly, and the edges where the slits 27 were made, became mutilated and liable to catch together. This was due to the 85 fact that the side walls lacked sufficient rigidity to remain in proper condition so that when closing the box the side walls of the lid member 21 would always swing over and pass down over the outer surfaces of the side walls of the bottom member 20. And sometimes the contents of the box would have a tendency 90 to press the side walls out, and a person handling the lid member would sometimes press its side walls in when closing the box.

This prevented the proper in-folding of the 95 creased and slotted intermediate wall connect-

ing sections which include the triangular tongue flaps 28. It had a tendency to tear the tongues 28 down or away on the crease lines which hingedly supported them.

5 The preceding description of objections to the box of the prior patent is necessary to an understanding of the advantages possessed by the present structure in which the double-thick side walls of both the bottom and the 10 cover or lid members not only increase the durability of the box as a whole but also serve to so hold or maintain in proper positions the intermediate connecting creased wall portions that the box can be opened and closed 15 many times without injury to said intermediate portions with their tongue flaps 28. So long as the latter are in good unmutilated condition, the box can be employed wide open to hold small articles on display, without risk 20 of such articles escaping. This is because the said intermediate wall portions are, excepting for the short slits 27, continuous between the side walls of the two members of the box. This latter is true of the box of the patent 25 referred to, but unless the connections between said side walls of the two box members remain in good condition of continuity they will not serve to retain small articles in the box. The present structure of double-thick 30 side walls provides for ensuring proper folding operations of the creased and slitted wall connecting sections when the box is being closed, thereby maintaining the box in useful condition.

35 I do not limit myself to a structure including the triangular tongue flaps 28 as the same may be omitted.

The advantage obtained by the presence of the notches or recesses 16 in the edges of the 40 side walls of the cover member is that when the cover member is closed down over the bottom member, there are small areas of the side walls of the bottom member always exposed or un-covered, which areas may be conveniently grasped between a finger and thumb of one hand to hold the bottom member steadily while the other hand is being used to raise the cover member. This enables the box to be opened without risk of spilling its 45 contents because the receptacle member of the box can be firmly held while the cover member is being raised. This feature of my invention 50 enables the boxes to be made of such relative proportions that the cover member fits the bottom member very closely. Such close fit, if there were no notches present, such as at 16, would render the act of opening the box liable to cause a spilling of the 55 contents when the cover member is lifted.

50 Having now described my invention, I claim:

A paper box comprising a bottom and lid and an intermediate section integral therewith, said bottom and lid having integral 65 doubled and glued side walls, the outer sec-

tions of the doubled side walls having completely connecting side wall portions each of which is diagonally creased and cut to provide inwardly collapsible triangular sections.

In testimony whereof I have affixed my 70 signature.

E. W. LABOMBARDE.
